DELLA V. LA MOTT, OF OAKLAND, AND CALHOUN J. DOGGETT, OF SAN FRANCISCO, CALIFORNIA.

INK HEATER FOR PRINTING PRESSES.

Application filed December 26, 1922. Serial No. 608,898.

To all whom it may concern:

Be it known that we, DELLA V. LA MOTT and CALHOUN J. DOGGETT, citizens of the United States, residing at Oakland, in the county of Alameda, and San Francisco, county of San Francisco, State of California, have invented new and useful Improvements in Ink Heaters for Printing Presses, of which the following is a specification.

This invention relates to improvements in printing presses and has to do with the application of heat to the printing plate and other parts of the press for the purpose of removing and eliminating the disadvantages and objections attending the operation of printing presses in cold weather and under undesirable atmospheric conditions whereby the printing operation and the printing are improved.

The primary object of the invention is to provide a heating appliance which is of simple and inexpensive construction and is capable of being readily attached to a printing press so as to apply heat to the ink plate and other parts of the press whereby the ink will be warmed and be subject to application in a better and more effective manner than when applied under cold conditions. The application of heat also tends to eliminate static electricity in the paper and to place and maintain in proper condition the printing cylinder, the paper packing of which in moist or damp atmospheric conditions, will often swell out of shape and become unfit for use.

A further object of the invention is to provide a heating attachment for cylinder printing presses in which the heat may be regulated to suit the conditions at hand and which is of such nature that it takes up little or no room and does not interfere with the ordinary operation of the press.

The invention possesses other advantages and features some of which, with the foregoing will be set forth at length in the following description where we shall outline in full that form of the invention which we have selected for illustration in the drawings accompanying and forming a part of the present specification. In said drawings we have shown one form of the construction of our invention, but it is to be understood that we do not limit ourselves to such form since the invention as expressed in the claims may be embodied in a plurality of forms.

Referring to the drawing:

Fig. 1 represents a fragmentary perspective view of a portion of the cylinder of a printing press showing it as it would appear when in use with the heating device of our invention.

Fig. 2 is a cross sectional view taken on line 2—2 of Fig. 1.

In carrying out our invention with cylinder presses, we mount adjacent to the ink plate, a heater which may derive its heat from any source but which preferably consists of a gas burner because of its simple, cheap construction and low cost of operation. The burner or heater is mounted above the ink plate so that the heat therefrom is directed onto said plate and the heat will also affect the cylinder. By the application of heat to the ink plate and associated elements, all of the disadvantages occurring incident to the operation of a printing press in undesirable atmospheric or cold conditions, such as the "off set" of the ink after being printed, the stickiness of the print, the objectionable static electricity conditions in the paper and the poor condition of the paper packing on the cylinder are removed. With our heater the ink is applied to the form in a more effective and desirable manner, especially in the coating of the solid portions of the type so that a better printing of such portions is effected. Ordinarily printing presses must be operated in warm temperatures and this requires heating of large rooms or buildings in order to secure the proper temperature. With our invention it is unnecessary to heat the entire room or building and maintain the same at a certain temperature for an effective operation of the press and by eliminating these former requirements, a saving in printing press operations will be effected.

The preferred embodiment of the invention as shown in the drawing is applied to a cylinder press and comprises a heater generally designated 1, which is mounted on the frame 2 of the press so as to extend across the ink plate 3 in front of the ink rolls 4 between the latter and the cylinder, which latter it is thought unnecessary to illustrate. The heater is preferably mounted several inches above the ink plate, its distance being varied depending upon the character of the heater. The heater is preferably constructed so that the heat therefrom is directed down-

wardly onto the ink plate and will have an appreciable effect on the rolls 4 and the cylinder, not shown. The type of heater which we have illustrated comprises two gas burners 5 and 6 in the nature of pipes having perforations in the under sides thereof through which perforations the fuel issues. These burners are arranged several inches apart parallel to one another and are held 10 on the frame 2 by suitable fastening devices 7 and 8. Across the top of these burners there is mounted a rectangular deflector plate 9 which is sufficiently wide to extend for a short distance beyond the sides of the 15 burners. This plate is preferably made of iron and is arranged so that the heat from the burners will be deflected downwardly onto the ink plate. A pipe 10 leading to a source of fuel supply, not shown, is connected by the usual fittings with the burners 5 and 6, and each burner is provided with a valve 11 to regulate the flame. The device of our invention is simple as to construction, compact, inexpensive and may be readily installed upon a printing press without requiring special or skilled labor.

With a press equipped with the device of our invention, in operating the press under cold and undesirable atmospheric conditions, 20 before putting the press into operation, the burners are lighted so that the heat therefrom will be directed onto the ink plate and will also affect the cylinder, not shown, and other parts of the press. In some instances 25 it may be necessary to operate the burner for a short time before the press is put into operation but this depends on the conditions at hand, inasmuch as the device of our invention is usually operated during the operation 30 of the press.

As the ink plate moves back and forth the working surface thereof has heat applied thereto in such manner as to maintain the ink in the proper soft condition and is otherwise effected so that the application of the ink to the type will be very effective and free from the objections attending when operating the press in cold and undesirable atmospheric conditions. As will be apparent 45 from the foregoing description and accompanying drawing, the use of the device of our invention in connection with printing presses will greatly improve printing operations and the character of the work.

We claim:

1. The combination with a printing press including an ink plate, of a burner extending across said ink plate above the latter and arranged to apply heat to the plate and a flat, deflector plate supported on the upper 60 side of the burner and arranged to deflect heat onto the plate, said deflector plate extending a short distance on opposite sides of the burner and extending over but a small part of the ink plate.

2. The combination with a printing press including an ink plate, of a burner extending across said ink plate above the latter and arranged to apply heat to the plate, a deflector plate of rectilinear outline fastened 70 on the upper side of and supported by the burner and arranged to deflect heat onto the plate, said burner comprising two pipes having burner orifices therein and a valve for each pipe, said deflector plate extending but a short distance beyond the outer sides of the pipes comprising the burner and extending over but a small portion of the ink plate.

CALHOUN J. DOGGETT.
DELLA V. LA MOTTE.
